CURTAIN FIXTURE

Ida Lundstrom, St. Louis, Mo.

Application March 7, 1949, Serial No. 80,073

1 Claim. (Cl. 211—103)

1

My invention relates to curtain fixtures and more particularly to vertically movable curtain rod bracket mounting members, and means for raising and lowering the members in unison.

An important object of the invention is to provide a pair of vertically movable mounting members so fashioned that any of the known types of curtain rod supporting brackets now secured to a window frame may be detachably secured to the mounting members instead of the window frame and raised, or lowered, in unison, by pull-cords.

A further object of the invention is to provide like curtain rod bracket mounting members which are pull-cord controlled for raising and lowering the curtain rod supporting brackets with their respective mounting members.

A further object of the invention is to provide a pair of curtain rod bracket mounting members which are carried by one end of a pair of pull-cords, and to which members any of the known types of curtain rod brackets may be secured to be raised and lowered with the mounting members by means of the pull-cords.

A still further and important object of the invention is to provide a pair of like curtain rod bracket mounting members which may be quickly and conveniently raised and lowered relative to the upper end of a window casing by means of a pair of pull-cords to allow a person standing on the floor to remove or attach curtains to a curtain rod attached to the bracket carried by the mounting members, thus obviating the necessity of a person standing on a chair, ladder, or other device.

Other objects and advantages of the invention will be apparent during the course of the following description.

Referring to the accompanying drawings, forming a part of this application, and in which like characters of reference are employed to denote like parts throughout the specification forming a part of the application;

Fig. 1 is a front elevation of my invention applied to a window frame, the mounting members supporting the curtain rod brackets and the curtain rod being shown as lowered in full lines by means of pull-cords, and in raised position in dotted lines.

Fig. 2 is a side view of Fig. 1.

Fig. 3 is a detail showing a mounting member in its raised position and hanging from a resting plate.

Fig. 4 is a view similar to Fig. 3, eliminating the resting plate, and showing the upper and lower flanges thereof as of the same size.

2

Fig. 5 is a top plan view of one of the curtain rod bracket mounting members.

Fig. 6 is a front elevation of one of the mounting members.

Fig. 7 is a view in perspective of a mounting member resting plate.

Fig. 8 shows a curtain rod bracket fastened to the mounting member by fastening devices passing through different slots than shown in Fig. 1.

Fig. 9 shows a curtain rod bracket fastened to the mounting member by fastening devices passing through different slots than shown in Figs. 1 and 8.

15 In the drawings, the reference character 10 designates the top cross member of a window casing; 11 designates the left side member of the window casing, and 12 designates the right side member of the window casing.

Further, in the drawings, wherein for the purpose of illustration only, is shown a preferred embodiment of my invention, the numerals 13 and 14 designate generally, a pair of like curtain rod bracket mounting members, which are preferably fashioned from sheet metal, although not necessarily so, as the members may be formed from other material such, for instance, as plastic, hard or semi-hard rubber, and the like. Each mounting member 13 and 14 consists of a flat plate like body portion 15 having a plurality of uninterrupted longitudinal slots arranged in spaced parallel relation with each other. The flat body portion 15 includes an upper flange 17 projecting rearwardly from the upper edge thereof, and a lower flange 18 projecting rearwardly from the lower edge of the flat body portion 15. The lower flange 18 is preferably, although not necessarily slightly longer than the upper flange 17.

20 The upper and lower body flanges 17 and 18 are provided midway their side edges with suitable pull-cord receiving openings 19 and 20.

25 Secured to the upper corner portions of the upper cross member of the window casing, are a pair of suitable eyelets 21 and 22. A third eyelet 23 is secured to the casing outwardly of the eyelet 22.

30 A pull-cord 24 passes through the eyelet 23 and then downwardly through the eyelet 21. The end portion 25 of the pull-cord 24 passes through the flange openings 19 and 20 of the mounting member 13 and lies behind the body portion 15. The free end of the cord portion 25 is provided with a knot 26 for the lower flange 18 of the mounting member 13 to rest upon.

35 A pull-cord 27 passes through the eyelet 23 and then downwardly through the eyelet 22.

40

45

50

55

The end portion 28 of the pull-cord 27 passes through the flange openings 19 and 20 of the mounting member 14 and lies behind the body portion 15. The free end of cord portion 28 is provided with a knot 29 for the lower flange 18 of the mounting member 14 to rest upon.

The portions of the pull-cords 24 and 27 outwardly beyond the eyelet 23 are connected with a suitable buckle 30 which acts as a stop by engaging the eyelet 23 when the mounting members 13 and 14 are lowered, and, when the mounting members are raised, the buckle lies below an anchor pin secured to the casing member 12 within reach of a person standing on the floor. The anchor pin 16 passes between the two pull-cords and the buckle engaging the pin holds the mounting members in their uppermost position.

The mounting members 13 and 14 each have the body portion 15 provided with a plurality of longitudinal slotted openings designated 31, 32, 33, 34 and 35 so that any of the known types of curtain rod brackets may be secured to the front face of the body portion 15 to be carried by the mounting members.

In Fig. 1, a curtain rod bracket 36 of a known type is secured to the body portions 15 of the mounting members by means of screws 37 passing through openings 38 and 39 in the bracket 36 and the slotted openings 32 in the body portions 15 of the mounting members 13 and 14. The screws are provided with nuts 40 which tighten against the back faces of the body portions 15 of the mounting members 13 and 14.

The reference character 41 designates a sectional curtain rod mounted at its ends on the pins 42 of the curtain rod brackets 36.

It will be clearly apparent that when the pull-cords are anchored to the casing pin that the mounting members 13 and 14, the brackets carried thereby, the curtain rods carried by the brackets, and curtains hung from the curtain rods will be in their raised position with respect to the window casing, and, when the cord buckle engages the eyelet 23 the mounting members 13 and 14 and parts carried thereby will be lowered to a position within easy reach of a person standing on the floor to remove, or attach curtains to the curtain rod.

The reference characters 43 and 44 designate a pair of like rest plates which may be secured to the window casing cross piece 10 by means of the eyelets 21 and 22. Each rest plate has a shoulder 45 and an inclined apron 46 so that when the mounting members are raised the aprons will guide the upper flanges 17 of the mounting members until the flanges rest upon the shoulders 45. This arrangement, when used, takes the load carried by the mounting members off the pull-cords. The weight of the mounting members, brackets, curtain rod and curtains will pull the mounting members off the shoulders 45 when tension on the pull-cords is released.

The rest plates 43 and 44 may, or may not be used, as desired, as the fixture works equally well either way.

By providing the body portion 15 of the mounting members 13 and 14 with the slotted openings in spaced parallel relation as shown, it will be readily apparent that known types of curtain rod brackets having various arrangements of fastener openings may be secured to the mounting members instead of being secured to the window casing, thus gaining the advantage of being able to raise and lower the curtains hung from the curtain rod by merely standing on the floor and operating the pull-cords, thus obviating the necessity of standing on a chair or ladder to remove curtains from the curtain rod and to attach curtains thereto.

The many advantages of the herein described invention will readily suggest themselves to those skilled, as well as the unskilled, in the art to which it appertains.

It is to be understood that the form of my invention herein described, is to be taken as a preferred example of the same, and that various changes in the shape, size and arrangement of the parts may be resorted to, without departing from the spirit of my invention, or the scope of the appended claim.

What I claim is:

In a curtain fixture, a pair of eyelets secured to a window casing adjacent the upper corners thereof, a third eyelet secured to the window casing and spaced outwardly from one of the first mentioned eyelets, a pair of pull-cords, said cords passing through the said pair of eyelets and both cords passing through the third eyelet and leading therefrom, a buckle connecting both cords beyond the third eyelet, a pull-cord anchor pin carried by one of the side members of the window casing, a mounting member having slotted openings carried by the end of each pull-cord below the said pair of eyelets, a curtain rod bracket detachably secured to each mounting member by fastening devices passing through said slotted openings, a curtain rod detachably mounted on each bracket, said mounting members adapted to be raised and lowered by the pull-cords, and a shouldered rest plate adapted to be secured to the window casing below said pair of eyelets for the mounting members to rest upon when in their raised positions.

IDA LUNDSTROM.
